UNITED STATES PATENT OFFICE.

ALLEN WALLACE, OF MOORESTOWN, NEW JERSEY, ASSIGNOR TO THE BALDWIN LOCOMOTIVE WORKS, OF PHILADELPHIA, PENNSYLVANIA, A CORPORATION OF PENNSYLVANIA.

FOOTPLATE FOR ELECTRIC LOCOMOTIVES.

1,343,698.

Specification of Letters Patent. Patented June 15, 1920.

Application filed February 20, 1919. Serial No. 278,252.

To all whom it may concern:

Be it known that I, ALLEN WALLACE, a citizen of the United States, and a resident of Moorestown, county of Burlington, State 5 of New Jersey, have invented certain Improvements in Footplates for Electric Locomotives, of which the following is a specification.

The object of my invention is to improve 10 the construction of the frame of an electric locomotive by providing a foot plate at each end of the main frame of the locomotive, formed in such a manner as to provide bearings and supports for a number of the moving parts of the locomotive structure and 15 also the bearing for the trucks at the ends of the frame.

In the accompanying drawings:—

Figure 1, is a diagrammatic plan view of a 20 locomotive frame, showing a foot plate at each end thereof;

Fig. 2, is an enlarged plan view of one of the foot plates;

Fig. 3, is a side view of the same;

25 Fig. 4, is an end view looking in the direction of the arrow 1, Fig. 2;

Fig. 5, is a plan view of the locomotive frame, showing the foot plate and certain parts of the locomotive mounted thereon;

30 Fig. 6, is a side view of the construction shown in Fig. 5;

Fig. 7, is a transverse sectional view on the line 7—7, Fig. 5;

Fig. 8, is a detached plan view of the 35 bumper; and

Fig. 9, is an end view of the same.

Referring to Fig. 1, 1, 1 are the side members of the frame of a locomotive. 2, 2 are the foot plates, one located at each end of 40 the frame structure and securely fastened to the side members. The two foot plates are identical so that it will only be necessary to describe one in detail.

In electric locomotive practice at the present 45 time, the two ends of the locomotive are usually similar in construction and the several parts of the locomotive are duplicated, such as the end trucks, the bumper, couplings, &c.

50 Referring to Figs. 2, 3 and 4, each foot plate has a flanged extension 3 at each side which is bolted, or riveted, to the side members 1 of the locomotive frame. At the op-

posite end is a portion 4 shaped to receive the bumper structure 5, Fig. 8. In some instances, the bumper structure may be made integral with the foot plate, but I prefer to make it separate so as to avoid intricate castings.

At the center of the foot plate is the bearing 6 for the center pin 7 of an end truck 8, Figs. 5 and 6, which is an ordinary four wheeled truck in the present instance. Directly in front of this bearing 6 is a bearing 9 for the pivot pin 10 of the draw bar of the coupling 11, which may be of any type desired. The foot plate is surfaced at 12 at each side of the center back of the bearing 6 for the fulcrum castings 13 on which are hung the equalizing beams 14, which are arranged at an angle in respect to the longitudinal line of the locomotive and are connected to a beam 15 at one end, which is supported on a pin 7^a within the pivot 7 of the truck 8, while the other end of each beam 75 14 is connected by a link 16 to one end of a spring 17. The opposite end of the spring is connected by a link 18 to the frame 1, while the spring rests on the box 19 in which the axle 20 of one of the driving wheels is 80 mounted.

On a line with the surfaced portions 12 for the fulcrum castings of the equalizing beams 14 are surfaces 21 to which are secured the cab spring supports 22, Fig. 5. At one end 85 of the foot plate are lugs 23 from which the brake hangers are suspended, and at the center at the same end as the lugs is a support 24 to which the bar 25 is secured which supports the driving motor or motor suspension. 90 The adjustable pilot 26 is also supported by the foot plate.

Each foot plate is an integral steel casting and may be surfaced at any point desired to receive any parts of the locomotive, and can 95 be bored or drilled at different points for the reception of the other elements than those shown.

I claim:—

1. A foot plate for an electric locomotive 100 frame arranged to be attached to either end of the main frame of a locomotive and having a single extension at the opposite end to which the bumper frame is secured and having a center bearing for a pivoted truck and 105 having an opening at the center bearing for

the passage of the center pin of the truck and having a pivot bearing for the draw bar of a coupling.

2. A foot plate for an electric locomotive frame arranged to be attached to either end of the main frame of the locomotive; having two extensions at one end arranged to be secured to the main frame of the locomotive and a single extension at the opposite end to which the bumper frame is secured; also having a center bearing for the truck, a pivot bearing for the draw bar of a coupling; and having surfaces on each side on which the fulcrum castings carrying the equalizing levers are mounted.

3. A foot plate for an electric locomotive made in a single casting of full width at one side and having extensions arranged to be secured to the main frame of a locomotive and tapered toward the opposite end, and having a reduced portion adapted to receive the bumper bar of the locomotive; a bearing for the pivot of a truck; a bearing for the draw bar of a coupling; and having lugs at the opposite end to which the brake hangers may be attached; and having supports for the motor, all cast integral with the said foot plate.

4. A foot plate for an electric locomotive made in a single casting and tapered from one end to the other, the wide end of said plate having extensions adapted to be secured to the main frames of the locomotive, the opposite end having a reduced projection to which the bumper bar of a locomotive can be attached and having, intermediate of the two ends, a center bearing for the center pin of one of the trucks, and also having a bearing for the pivot pin of the draw bar of a coupling, which extends beyond the bumper bar, and having lugs at the opposite end from which the brake hangers are hung, and having at the center of said end a support for

a motor, and having, between said support and the truck, pivot bearing surfaces on 45 which the fulcrum castings of the equalizing mechanism are mounted as well as the cab spring supports.

5. In a locomotive frame, the combination of two main side frames with two cast foot 50 plates, one secured at one end of the main frame and the other secured at the other end, said foot plates being identical in form and each having an end reduced in width; a bumper frame secured to the reduced portion 55 of the foot plate, each foot plate having a pivot bearing; a truck mounted under each foot plate and having a pivot pin extending into the bearings; fulcrum castings secured to each foot plate; an equalizing lever pivotally mounted on each fulcrum casting; and a cross bar carried by the pivot pin of the truck and connected to one end of each equalizing lever.

6. In a locomotive frame, the combination 65 of two main frames with two cast foot plates, one secured at one end of the main frame and the other secured at the other end, said foot plates being identical in form and each having an end reduced in width; a bumper 70 frame secured to the reduced portion of the foot plate, each foot plate having a pivot bearing; a truck mounted under each foot plate and having a pivot pin extending into the bearings; fulcrum castings secured to 75 each foot plate; an equalizing lever pivotally mounted on each fulcrum casting; a cross bar carried by the pivot pin of the truck and connected to one end of each equalizing lever; and cab spring supports on each of the 80 foot plates at either side of the center and substantially in a line with the pedestals of the equalizing gear.

In witness whereof I affix my signature.

ALLEN WALLACE
